UNITED STATES PATENT OFFICE

CLAUDE C. COEN, OF CULVER, OREGON; MAGGIE L. COEN ADMINISTRATRIX OF SAID
CLAUDE C. COEN, DECEASED

CURTAIN FIXTURE

Application filed November 5, 1931. Serial No. 573,257.

One of the principal objects of this invention is to provide a tieback member for curtains adapted to form a runway for the shade back of the member of sufficient depth to permit the shade being raised or lowered without catching, tearing, or mussing the lace curtain.

Another object of this invention is to provide simple, inexpensive and attractive means whereby curtains and other draperies may be held in graceful folds and the tieback which restrains the draperies may be easily applied and set to extend across the curtains in a horizontal position or at an inclination upward or downward therefrom. A further object of the invention is to provide a holder which may be adjusted to the width of the folds desired to appear in the draperies or curtains, and other objects of the invention will appear incidentally in the course of the following description.

In the accompanying drawing,

Fig. 1 is an elevation of a window having curtains draped thereat and held by my improved tieback,

Fig. 2 is an enlarged horizontal section on the line 2—2 of Fig. 1,

Fig. 3 is an enlarged vertical section on the line 3—3 of Fig. 1,

Fig. 4 is a detail perspective view of the bracket members showing the same separated but in their proper approximate relation.

In carrying out the present invention, there is provided a base bracket consisting of a plate 1 having openings 2 therethrough near its upper and lower ends through which screws or other pointed fastenings may be inserted to secure the bracket upon the edge or side of a window frame, indicated at 3. From the lower end of the plate 1, the metal of the plate is extended outwardly and then upwardly in a fold, shown most clearly at 4 in Fig. 4, and the free end of the upturned portion is pressed outwardly, as shown at 5, whereby a grooved or concave finger is formed to engage and hold the tieback support, the main portion of the plate being arcuate to provide a mating groove or bearing portion, as clearly shown. The tieback support is formed from a sheet metal

blank having its major portion flat, as shown at 6, and provided with re-entrant flanges or guides 7 along its upper and lower edges. From one end of the flat portion 6, the blank is bent at a right angle to form an arm 8 which will extend toward the window frame and terminates in a cylindrical nipple 9 which is engageable between the finger 5 and the base 1 of the main supporting bracket. Inasmuch as the nipple 9 has a circular cross section, it may be rotated in its bearing, furnished by the plate 1 and the finger 5, so that the outer portion 6 of the support may extend across the window in a horizontal plane or may be set to extend upwardly or downwardly from such a plane. Slidably fitted within the guides or flanges 7 is a flat extension member 10 which has its outer extremity turned slightly outward, as shown at 11, and may be slid longitudinally within the guides 7 so that its free end will be set at a greater or less distance from the end of the member 6. The tieback support may thus be adjusted to the desired width of the folded portion of the drapery. An indentation 12 may be produced in the member 6, near its outer end, so as to frictionally hold the extension 10 in its set position.

In use, the curtains, indicated at 13, are hung at the window in the usual or any approved manner and the tiebacks 14 are placed around the curtains at the proper point, as indicated in Fig. 1. The tiebacks are constructed with an upper portion or hem 15 which is adapted to be engaged about the supporting member including the elements 6 and 10, and from said hem or upper portion a flounce or ruffle 16 may depend to impart the desired attractive finish. In fitting the tieback to the supporting bracket, one end of the tieback is brought into engagement with the outer end of the extension 10 and is then worked over the same until it reaches the right angular portion 8. The greater portion of the length of the tieback is then carried around in front of the curtains or draperies, as will be understood upon reference to Figs. 1 and 2, and the free end of the same is carried around to the arm 8 and fastened thereto in any convenient manner, as by wrapping

a portion of the same about the arm and then sewing the meeting portions.

From the foregoing description, taken in connection with the accompanying drawing, it will be seen that I have provided an exceedingly simple device by the use of which curtains and draperies may be very easily and effectually secured and held in the desired formation. Any desired tieback may be used in connection with the support and may be set in any position which conforms to the taste and desires of the user. To vary the inclination of the supporting member 6, it is necessary merely to rotate the support axially about the nipple 9 as a center and it will be held in the set position without further attention, the finger 5 possessing sufficient resiliency to permit the support to be easily adjusted but at the same time exert sufficient friction thereon to hold it normally in any position in which it may be set. It will be noted, particularly upon reference to Fig. 2, that the supporting member 6 stands clear of but substantially parallel with the window frame and, in effect, provides a runway in which a shade 17 may be raised or lowered without catching in lace curtains and damaging the same. The runway for the shade 17 may be said to be produced by the combined length of the nipple 9 and arm 8 which form the pivot or journal of the tieback member. It is found advantageous to make the journal about one and one-half inches long to provide a runway between the window frame and the tieback member of one and one-half inches depth, more or less, which, in practice, is found to be sufficient to permit the shade to be moved up and down without catching, tearing, or mussing the lace curtains.

Having thus described the invention, I claim,

1. A device for the purpose set forth comprising a base plate constructed to be secured upon a window frame, a resilient finger carried by the lower end of said plate and cooperating therewith, and a supporting member having one terminal formed into a journal at a right angle to the member to engage horizontally between said plate and said finger and be rotatably frictionally held thereby, whereby the member may rotate in a vertical plane, the major portion of said member being constructed to extend across the window frame.

2. A device for the purpose set forth com-

prising a base plate constructed to be secured upon a window frame, a resilient finger carried by the lower end of said plate and upstanding to cooperate with said plate, and a supporting member adapted to extend across the front of the window frame and constructed at one end with a journal disposed at a right angle to its major portion and adapted to rotatably and detachably fit between the base plate and resilient finger and be frictionally held thereby, whereby the member may rock in a vertical plane and be frictionally held in a set position.

3. A device for the purpose set forth comprising a resilient holding bracket adapted to be secured upon a window frame, a tieback support constructed at one end with a journal to engage horizontally in and be frictionally held by the holding bracket and having its major portion extending across the window frame from said end at a right angle thereto whereby it may rock in a vertical plane, and an extension slidably engaged in the tieback support.

4. In a device of the class described, a curtain tieback member, and means for supporting the tieback member upon a window frame in sufficiently spaced relation with respect to the frame whereby a shade is free to be moved vertically without interference with the tieback member.

5. In a device of the class described, a curtain tieback member, means for rotatably supporting the tieback member upon a window frame in sufficiently spaced relation with respect to the frame whereby a shade is free to be moved vertically without interference with the tieback member, and means for holding the tieback member at any degree of rotation.

6. A window curtain holder comprising a bar having one end forming a journal disposed at substantially a right angle to the bar to be extended toward and mounted upon a window frame whereby the bar will be supported at the front of the frame in spaced relation thereto for rocking movement in a vertical plane, said journal being of sufficient length to space said bar sufficiently from the window frame to provide a runway between the bar and the frame adapted to permit a window shade being moved vertically therein without interference with the bar and curtain held thereby.

In testimony whereof I affix my signature.

CLAUDE C. COEN. [L. S.]
